UNITED STATES PATENT OFFICE.

JOHN MARTIN DAVIS, OF GREAT FALLS, MONTANA.

PLASTERER'S HAWK.

SPECIFICATION forming part of Letters Patent No. 534,741, dated February 26, 1895.

Application filed May 9, 1894. Serial No. 510,624. (No model.)

To all whom it may concern:

Be it known that I, JOHN MARTIN DAVIS, a citizen of the United States of America, residing at Great Falls, in the county of Cascade 5 and State of Montana, have invented certain new and useful Improvements in Plasterers' Hawks, of which the following is a specification, reference being had therein to the accompanying drawings.

10 Heretofore plasterers' hawks have been constructed of a board having a dovetail shaped mortise in the rear side extending transversely of the grain or the fibers of the wood. A corresponding shaped cleat of wood is driven 15 into this mortise to strengthen and prevent warping of the board, and a handle is permanently attached to the hawk usually by having a tenon at its end, which is fitted into a mortise in the cleat and the board. A hawk 20 of this construction can only be made by a skilled mechanic and having the handles permanently attached is unhandy and makes a bulky package.

The purpose of this invention is to provide 25 a hawk having a detachable handle which can be readily removed and quickly attached to the board at will, and which when in place will be firm and rigid; also to devise means whereby any board of suitable dimensions 30 can be converted into a hawk by the attachment thereto of the provisions hereinafter more particularly set forth.

In the annexed drawings,—Figure 1 is a bottom perspective view of a hawk showing the 35 application of the invention. Fig. 2 is a detail view of the handle. Fig. 3 is a view of the plate. Fig. 4 is a detail view of a portion of the hawk board showing the metal wear plate in position.

40 A represents the hawk board which is usually about twelve by twelve inches square and tapers in thickness from about four inches from each edge outward to the edges to reduce the weight.

45 B is a metal plate of sufficient thickness to give stability to the board and prevent warping. This plate is long and narrow and tapers in width from a short distance from each end and has openings to receive the screws 50 or similar fastenings a by means of which it is fastened to the board. An opening C is provided about the center of the plate to re-

ceive the end of the handle D. Notches b in the edge of the opening C form lips e which engage with corresponding lips d on the end of the handle and retain the latter in place. These lips e have a certain amount of resiliency to give slightly when turning the handle to force the lips d beneath the said lips e. The notches b are equidistant and of a length corresponding to the length of the lips e thereby facilitating the attachment of the handles to the board.

The handle is tubular and has its end notched, the portions between the notches 65 being turned outward at about right angles to provide the lips d which correspond in position and number with the notches b to pass through the same in the operation of attaching and removing the handle. One end of the lip is beveled to facilitate the entrance under the lips e.

A wear plate is attached to the board A opposite the opening C to receive the end thrust of the handle and prevent the same cutting into the soft board. Plate B is not mortised into the board but fastened on the under side thereof crosswise of the grain and the middle portion is slightly bulged to cause the lips e to stand out a proper distance to 80 receive the lips d. To attach the handle the lips d are brought in register with the notches b through which they pass, the handle being given a turn to cause the lips d to pass beneath the lips e by which the handle is retained in place. If desired interlocking projections may be provided in the opposing faces of the lips d and e to retain in place 85 against accidental displacement. To detach the handle the reverse of the operation just 90 described is practiced.

I claim—

1. The combination with a hawk-board, of a flat metal plate arranged transversely of the fibers of the hawk-board and secured to 95 its nether side by screws, or similar fastenings, and having a centrally disposed opening provided in its edges with alternate notches and lips, a wear plate secured to the board opposite the said central opening and a handle removably attached to the hawk-board and having lateral extensions corresponding in position and number with the notches in the flat metal plate through which they pass 100.

and are engaged with the lips by a partial turn, substantially as described.

2. A hawk composed of a hawk-board, an oblong plate secured to its nether side and disposed transversely of the fibers, and having a centrally disposed opening provided in its edges with alternate notches and lips, that portion bordering upon the opening being bulged outwardly, and a handle having lateral extensions to be passed through the said

notches and engaged with the lips, substantially as described and for the purpose specified.

In testimony whereof I affix my signature in presence of two witnesses.

JOHN MARTIN DAVIS.
